main in an upraised or collapsed condition much in the manner illustrated in Figure 1 of the drawings but that when it is desired to extend the same it is only necessary to pull the bottom rail downwardly through a distance of the order of the length of the unstretched ladder tapes 18 to thereby stretch the ladder tapes 18 to roughly twice their unstretched length, as shown in Fig. 2, and then pass the studs 24 beneath the brackets 25a, as illustrated in Figure 8 of the drawings and then allow the elasticity of the ladder tapes 18 to pull the bottom rail and its attendant mechanisms upwardly so that the studs 24 will be engaged by the dependant teeth 26 of the bracket 25a, as illustrated in Figure 5 of the drawings.

When it is desired to tilt the slats 20, it is only necessary to grasp the handles 23 and press the bottom rail 17 downwardly to the position shown in Figure 8 and thereafter turn the bottom rail 17 to the desired angle and then allow the same to be moved upwardly by the elasticity of the ladder tapes to again be gripped by the teeth 26, as illustrated, for example, in Figure 6 of the drawings.

It will also be apparent that the slats 20 may be removed at any time by simply sliding the same transversely out of the members 19 and that the recesses 21 may be very shallow indeed as their sole function is to act as a guide for the alignment vertically of the slats and not for holding the same.

While but one form of the invention has been shown and described herein, it will be readily apparent to those skilled in the art that many minor modifications may be made without departing from the spirit of the invention or the scope of the appended claims.

What is claimed is:

1. A cordless Venetian blind comprising an upper horizontally pivoted tilt rail; a plurality of pairs of stretchable elastic ladder tapes extending downwardly from said tilt rail, the ladder

tapes of each pair being disposed on opposite sides of said tilt rail; a plurality of slat supporting cross bands extending between the tapes of each pair at spaced points therealong; slats extending between adjacent pairs of ladder tapes and supported by said cross bands; and a bottom rail supported by said tapes and extending intermediate the tapes of each pair, the stretchability of said tapes being sufficient to permit said bottom rail to be repeatedly moved downwardly through a distance of the order of the length of the unstretched tapes.

2. A cordless Venetian blind according to claim 1, further comprising movable angular position locking means carried by said bottom rail; and fixed locking means removably engageable with said movable locking means in a plurality of angular relationships therewith.

3. A cordless Venetian blind according to claim 2 wherein the fixed locking means is engageable with the movable locking means in a position of the lower rail in which the tapes are stretched.

4. A cordless Venetian blind according to claim 3 wherein the fixed locking means is hook-shaped having serrations disposed about its inner periphery and the movable locking means comprises a circular member having peripheral serrations shaped for engagement with the serrations of said hook.
